BICYCLE FRAME

Thomas D. Seifert, 1126 Fairview Ave., Apt. 203,
Arcadia, Calif. 91006

Filed Nov. 4, 1974, Ser. No. 520,631

Term of patent 14 years

Int. Cl. D12—11

U.S. Cl. D12—111

Fig. 2.

Fig. 3.

FIG. 1 is a side elevational view of a bicycle frame showing my new design;

FIG. 2 is a rear perspective view thereof; and

FIG. 3 is a frontal perspective view thereof.

The broken line showing of bicycle components including wheels, drive chain and sprocket, pedals, seat and seat post, fork and handle bars is for purposes of illustration only.

I claim:

The ornamental design for a bicycle frame, as shown and described.
